US00D885909S

(12) **United States Design Patent** (10) **Patent No.:** **US D885,909 S**
Franzone, Jr. et al. (45) **Date of Patent:** **** Jun. 2, 2020**

(54) **DISPLAY HEADER HOOK**

(71) Applicant: **ALLEN FIELD COMPANY, INC.**,
 Brightwaters, NY (US)

(72) Inventors: **Andrew Franzone, Jr.**, Bay Shore, NY
 (US); **Robert Ahearn**, Massapequa, NY
 (US); **Eric Seger**, Wantagh, NY (US)

(73) Assignee: **ALLEN FIELD COMPANY, INC.**,
 Brightwaters, NY (US)

(**) Term: **15 Years**

(21) Appl. No.: **29/688,252**

(22) Filed: **Apr. 19, 2019**
